VACUUM NOZZLE

Jörgen F. H. Fechtenburg, Cheltenham Township, Montgomery County, Pa.

Application March 1, 1935, Serial No. 8,943

7 Claims. (Cl. 15—158)

This invention relates to nozzles for vacuum cleaners, and especially to those used in the home, office, etc. for cleaning pile carpets, upholstered furniture, draperies, and the like.

One object of the present invention is to provide a nozzle which will be highly efficient in the picking up of cat, dog, or other animal hair, threads, lints, and other materials which have a tendency to cling to the pile or other surface being cleaned, as by becoming entangled, for example, with fibers of the yarns of which the pile or other surface is composed.

More specifically, the present invention relates to the provision of vacuum cleaner nozzle with a brush disposed at one or both sides of the normal suction slot of the nozzle and arranged in such relation to the vacuum slot that when the nozzle is moved in one direction the ends of the bristles of the brush are projected down below the base or sledding surface of the nozzle into the pile, below the top surface thereof, to effect a raking action through the outer free ends of the pile tufts, whereby any threads, hairs, or lints which may have become buried to some extent in the pile will be caught by the bristles of the brush and upon movement of the nozzle in the opposite direction such collected material will be delivered into the mouth of the vacuum slot of the nozzle by a bending or rocking action of the bristles causing the free ends of the bristles to move from the raking position remote to the slot to the delivery position immediately adjacent the slot, wherein the material collected by the bristles is lifted by the brush clear of the surface being cleaned, to be caught by the air rushing into the vacuum slot of the nozzle.

Another object of the invention is to provide a brush of the character above noted on each of the opposite sides of the vacuum slot whereby while one brush is effecting a raking action of the surface as the nozzle is moved in one direction the other of said brushes is effecting a delivery action of material previously collected thereby; and wherein the movement of the nozzle in the opposite direction will change the relation of the two brushes so that the one having just completed a raking action moves into the delivery position and the one having completed the delivery operation is moved into the raking position.

Another object of the invention is to construct the nozzle in such a manner that the hair, threads, lint, or other material over which the nozzle is moved cannot become entangled in the bristles of the brush.

Another object of the invention is to construct

the nozzle in such a manner that the air drawn into the vacuum slot of the suction nozzle must first pass along and around the brush, longitudinally of the bristles thereof, whereby a self-cleaning brush is provided.

Another object of the invention is to construct the nozzle with a draft slot adjacent and parallel to the suction slot with its upper air intake end disposed well above the surface being cleaned whereby clean air is at all times drawn downwardly through the draft slot toward the suction slot, and to mount the brush in the down draft slot for effecting self-cleaning of the brush.

Another object of the invention is to provide mechanism whereby for normal cleaning, for the removal of dust, grit and material other than hair, threads, or lints, the brush or brushes at each or either side of the suction slot in the nozzle may be readily moved to an inoperative position wherein the ends of the bristles of the brush are withdrawn to a non-raking position above the plane of the sledding surface of the nozzle.

Another object of the invention is to construct and mount the brushes in such a manner that each brush and the mounting therefor may be readily removed from the nozzle as a unit.

Another object of the invention is to construct the brush and mounting in such a manner that the extent of projection of the bristles of the brush beyond the sledding surface of the nozzle may be readily adjusted to control the extent of penetration of the bristles into the pile of the surface being cleaned and to permit gradual outward feeding of the bristles to an effective raking position as the ends of the bristles wear away over an extended period of service.

Other objects of the invention and the novel features of the construction by which such objects are attained will be fully disclosed hereinafter, reference being had to the accompanying drawings; of which:

Fig. 1 is a plan view partly in section of a nozzle embodying the principles of the present invention;

Fig. 2 is a transverse sectional elevation taken on the line 2—2, Fig. 1, and showing the action of the bristles at the opposite sides of the vacuum slot as the nozzle is moved in one direction;

Fig. 3 is a view similar to Fig. 2 and showing the action of the brushes as the nozzle is moved in the opposite direction;

Fig. 4 is an inverted plan view of the structure shown in Figs. 1, 2 and 3;

Fig. 5 is a longitudinal sectional elevation taken on the line 5—5, Fig. 1;

Fig. 6 is a view similar to Fig. 1, illustrating the feature of independent adjustability of the 5 pair of brushes to operative and inoperative positions with respect to the sledding surface of the nozzle;

Fig. 7 is a longitudinal sectional elevation taken on the line 7—7, Fig. 6;

Fig. 8 is a view similar to Figs. 1 and 6 illustrating the feature of simultaneous operation of the 10 brushes to and from an inoperative position within the nozzle;

Fig. 9 is a perspective view of a detail of the 15 construction shown in Fig. 8;

Figs. 10 and 11 respectively illustrate different ways of removably securing the brush units in position within the nozzle;

Fig. 12 is a view similar to Fig. 2 illustrating 20 a modification of the invention for the purpose of providing a more acute delivery action of the brushes;

Fig. 13 is a longitudinal sectional elevation taken on the line 13—13, Fig. 12;

Fig. 14 is a side elevation of that type of nozzle 25 shown in Figs. 1 to 13 inclusive and arranged to be operated by means of a vacuum type handle, with a swivel connection between the handle and the nozzle whereby free sledding action of the 30 nozzle is provided over the surface being cleaned and whereby the handle may be turned with respect to the nozzle for projecting the nozzle under low pieces of furniture, etc.;

Fig. 15 is a side elevation partly in section of a 35 modified form of the invention wherein the nozzle is connected directly to the vacuum machine;

Fig. 16 is a longitudinal sectional elevation taken on the line 16—16, Fig. 15;

Fig. 17 is a fragmentary plan view illustrating 40 one end of the nozzle shown in Figs. 15 and 16;

Fig. 18 is a transverse sectional elevation illustrating a nozzle made in accordance with the principles of the present invention and adapted particularly for use in cleaning upholstered furniture, draperies, etc.;

Fig. 19 is a sectional plan view taken on the line 19—19, Fig. 18;

Fig. 20 is a longitudinal sectional elevation taken on the line 20—20, Fig. 19;

Fig. 21 is a view similar to Fig. 18 and embodying the acute bristle-bending feature similar to the illustration of Fig. 12; and

Fig. 22 is a longitudinal sectional elevation taken on the line 22—22, Fig. 21.

Fig. 23 is a simpler form of the invention shown in Figs. 1 to 6 inclusive, the nozzle 1 is of more or less usual construction as a whole, being of the relatively elongated suction slot type but differing from the usual construction of this type of 50 nozzle in that the base 2 of the nozzle is considerably wider than the bases of the usual vacuum nozzles.

The base 2 in the present case is provided with a central longitudinal base or sledding surface 55 3 which is substantially flat. The base 2 includes relatively wide front and back lips 4 and 5 respectively having underneath or sledding surfaces 6 and 7 which are disposed at opposite angles respectively and with respect to the plane of the 60 central flat portion 3, whereby free sledding action of the nozzle over the surface being cleaned is made possible.

Intermediate the lips 4 and 5, the top side of the base 2 of the nozzle is provided with a longitudinally extending rib 8, adjacent each of the

opposite ends of the nozzle, and intermediate the inner ends of said ribs 8 is an enlarged substantially rectangular boss 9 constituting the central main portion of the nozzle.

Centrally disposed with respect to the rectangular boss 9 and projecting vertically from the central portion thereof, longitudinally and transversely speaking, is a more or less triangular rib extension 10 which is aligned with the end ribs 8 and projects vertically from the top surface of the boss 9.

The rear side of the top central rib 10 of the nozzle is provided with a substantially cylindrical boss 11, the axis of which in the preferred form of the invention is disposed substantially 15 parallel to the flat plane of the central portion 3 of the sledding surface of the nozzle.

Centrally disposed with respect to the sledding surface of the nozzle and extending substantially from end to end thereof is the vacuum suction 20 slot 12, the depth of which varies from its minimum depth in the ribs 8, 8 adjacent each of the opposite ends of the nozzle and increasing gradually toward the central portion 9 of the nozzle, as indicated at 13, 13, whereupon the base of the 25 slot 12 assumes a rather acute angle at each of its sides within the vertical central rib portion 10, as indicated at 14, 14 in Fig. 5, said slot centrally terminating at and in and communicating directly with the circular axial cavity 16 of the 30 rearwardly extending boss 11.

At either the front, back or at both sides of and parallel to the vacuum slot 12 of the nozzle 1 and located within the central rectangular boss 9 thereof, said nozzle is provided with an elongated draft slot 17 which within the central portion of the nozzle is separated from the vacuum slot by a relatively thin vertical wall 18.

The slots 17, 17 extend completely through the nozzle 1, vertically from the flat plane of the 40 central portion 3 of the sledding surface of the nozzle to the upper surface 19 of the central rectangular boss 9.

Normally the slots 17, 17 provide for what may be termed a concentrated down draft for the 45 nozzle, whereby, during normal operation of the device the air is drawn and rushes down through the slots 17, 17 and around the lower edges of the walls 18, 18 and into the vacuum slot 12 of the nozzle, whereby grit and tramped-in tobacco 50 ashes, etc. is more efficiently removed from the pile of the carpet or other fabric being cleaned. Such concentrated down draft, however, will not in itself effectively remove animal hair, threads and lint, or other material which has a tendency to mat with or become entangled in the fibers of the fabric and in order to make the nozzle efficient in this respect the present invention embodies the feature of providing suitable brushes in one or the other or both of the slots 17, 17, with the lower 55 ends of the bristles exposed preferably a very slight distance below the flat portion 3 of the sledding surface of the nozzle whereby the ends of said bristles project just a slight distance into and below the surface of the pile of the fabric 60 being cleaned and thereby effect a gentle raking action of the free outer ends of the pile of the fabric being cleaned.

The present invention further contemplates the mounting of the brush or brushes in such a 70 manner that the degree of the raking action may be minutely varied to meet varying conditions and different materials encountered, although for all practical purposes it has been found that a projection of the bristles to an extent not ex- 75

ceeding $\frac{1}{2}$ of an inch is highly efficient and is capable of removing such material as goat hair which has been trampled into the pile of the fabric. Goat hair, by those familiar with the art, is considered to be the hardest material to remove from a pile of fabric.

In order that the brush or brushes may be removed from one or the other or both of the slots 17, 17 easily and at any time desired, to take advantage of the full down draft provided by the slots 17, 17, when no particularly clinging material is being encountered in cleaning, the brushes are mounted in readily removable carriers 20, 20 respectively.

Each of the carriers 20 in the preferred form of the invention comprises a single side wall 21 adapted to extend substantially the full length of the slot 17 into which the carrier 20 is to be fitted, said walls 21, 21 being adapted for positioning at that side of the slot 17 in each instance which is remote from the wall 18 lying between the draft slot 17 and the vacuum slot 12 of the nozzle.

At each end of the carrier 20 and projecting laterally from the wall 21 thereof is a relatively broad lug 22. Intermediate the lugs 22, 22 is a series of parallel laterally projecting fins or ribs 23 which extend from the wall 21 of the carrier 20 to the wall 18 of the nozzle.

Within the central portion 14 of the vacuum slot 12 the lower edges of the walls 18, 18 of the nozzle are disposed in a plane slightly inward from the plane of the flat portion 3 of the sledging surface of the nozzle, as clearly illustrated in Figs. 2 and 3, and the lower inner edges of the fins or ribs 23 are provided with shouldered corners 24 which pass around and engage the under surface of the wall 18.

Disposed in each of the cavities 25, which are formed by and between adjacent ribs 23, 23, a number of bristles 26 are grouped together to form a brush unit, within each of the said cavities, each unit being relatively independent of its neighbor.

While the number of bristles constituting each brush unit may vary as desired, in actual practice it has been found that a relatively small number of bristles in each of the cavities 25 will suffice to produce high efficiency insofar as removal of hair, thread, or lint is concerned. The smaller the number of bristles the smaller the possibilities of material becoming entangled in the bristles.

Entanglement of hairs and other materials in the bristles, particularly hairs, is further prevented by the fact that such hairs will normally span one or more of the spaces 25 by resting against the lower surfaces of two or more of the ribs 23 and will thereby be prevented from being pushed up into the bristles of the brush, as by downward pressure applied to the nozzle during the cleaning operation.

In addition to the functioning of the ribs 23 in preventing material being pressed up into the bristles of the brush the down draft of the air rushing into the nozzle through the slots 17, 17 which causes the air to travel at high velocity in the downward direction longitudinally of and around the bristles of the brush, from the upper back portion of the brush toward the lower free ends of the bristles, strips such material from the projecting ends of the bristles and from the lower surface of the ribs and carries the hairs or other material around the lower edges of the walls 18 and up into the vacuum slot 12. Thus the brush is made a self-cleaning proposition.

As shown in Figs. 2 and 3, the bristles are

mounted in the slots 17 toward or against the outer side walls thereof, that is, immediately adjacent the walls 21 of the carriers 20, 20 respectively, and due to the slight projection of the lower ends of the bristles below the flat surface 3 of the nozzle when the nozzle is moved in one direction, for example, in the direction indicated by the arrow *a* in Fig. 2, the lower ends of the bristles of the brush in the rear slot 17 will lie flatly against the wall 21 of the carrier in said slot and be stiffly supported thereby, whereby the slight projecting ends of the bristles will be prevented from bending and sliding freely over the surface of the fabric being cleaned and will be held substantially perpendicular to the plane 15 of the flat portion 3 of the nozzle, whereby the raking effect is obtained.

During the above noted movement of the nozzle the bristles of the brush in the front slot 17 are free to move, flex or rock within the cavities 25 in which they are respectively confined, which causes said bristles to move away from the wall 21 of the carrier in the front slot 17. In such flexing or bending the lower ends of said bristles move inwardly to a position below the plane of the sledging surface 3 in a position immediately adjacent the wall 18 which is disposed between the front slot 17 and the vacuum slot 12 and in such bending and raising of the bristles any material, hairs, threads, or lint which have been caught or collected by the bristles in the front slot during a previous backward movement of the nozzle in the direction of the arrow *b*, Fig. 3, are delivered directly to the mouth of the vacuum slot 12 of the nozzle and the draft passing downwardly through the front slot 17 and around the lower edge of the wall 18 between said front slot 17 and the vacuum slot 12 will strip such material from the bristles of the brush and carry it up into the vacuum nozzle as clearly illustrated in Fig. 2.

In order to prevent hair or other material which may be in suspension in the air surrounding the nozzle from being drawn down into the down draft slots 17 and thereby becoming clogged in the upper part of the brush each carrier 20 is provided with a substantially horizontal top wall 27 which is provided with small perforations 28 which permit free access of the air and at the same time prevent suspended material from passing down into the slot.

The ribs 23 extend up into the slots 17 a substantial distance above the under surface of the wall 18 of the nozzle and between the upper edges of said ribs and the under surface of the top wall 27 of the carrier the bristles of the brush are secured in a back bar 30 which, as illustrated in Fig. 1 for example, is of a more or less corrugated nature, permitting free downward passage of the air through the slot 17.

Each of the end lugs 22, 22 of each carrier 20 is provided with a recess 29 into which the opposite ends of the back bar 30 extend. The opposite ends of the back bar 30 are bored and threaded for the reception of supporting and adjusting screws 31, 31, each of which has a plain end 32, having bearing in lug 22 below the cavity 29, and an upper non-thread portion 33 immediately adjacent the underside of the head 34 of said screw, which also has bearing in the lug 22 above the cavity 29.

Intermediate the top side of the back bar 30 and the under side of the upper bearing for the screw 31, each screw is provided with a compression spring 35 which tends at all times to force the back bar downwardly within the carrier 20.

keeping the under side of the head 34 firmly seated against the upper surface of the carrier 20, while the plain ends 32 and 33 of each screw are free to slide axially in their bearings in said carrier. Thus the springs 35 perform the double function of projecting the bristles of the brush outwardly, upon turning of the screws 31 in one direction, and of establishing rigidity, against vibration or rattling of the brush backs during operation of the device.

In order to provide for the readily removability of the carriers 20 and the brushes carried thereby from the slot 17 in each instance, the end wall of the slot and the end wall of the carrier are provided with cooperating shoulders 36 and 37 which limit the upward movement of the carrier in and with respect to the slot 17. Such upward movement of the carrier within the slot 17 may be provided by various mechanisms and in the present instance a simple spring-pressed plunger arrangement comprising a ball 38 operable in a cavity 39 formed in the boss 9 and cooperating with and bearing against an angular wall 40 formed in the carrier 20, effects a camming action which tends at all times to retain the carrier in the slot.

With the above noted construction the carrier 20 may be readily removed from the slot 17 by merely pressing downwardly against the upper surface of the carrier, whereby the angular surface 40 produces a camming action against the spring-pressed ball 38, at each end of the carrier, forcing said balls inwardly against the action of their springs 41 to the planes of the end walls of the slot which permits the carrier to slip freely out of the slot 17.

Obviously, reinsertion of the carrier 20 may be readily effected by merely pressing the carrier 20 upwardly in the slot 17 until the balls 38 at the opposite ends of the carrier snap under the angular surfaces 40, 40 in the opposite ends respectively of the carrier.

Fig. 11 illustrates a modification of the above noted mechanism, wherein the carrier 20 at each of its opposite ends is provided with a spring latch 42 having a hook end 43 arranged to snap over the top surface 19 of the boss 9 of the nozzle immediately adjacent the opposite ends of the slot 17.

In that form of the device shown in Fig. 10, the carriers are rigidly, though removably, secured in the nozzle by means of screws 44; and in that form of the invention shown in Fig. 7 the spring-pressed balls 38 are carried by the carrier 20 and operate against angular camming surfaces formed in the end walls of the slots in which the carriers are disposed.

In that form of the invention shown in Figs. 6 and 7, the brushes may be moved to an inoperative position, that is, to a position inwardly disposed with respect to the sledding surface of the nozzle, without removal of the carriers from the nozzle and for this purpose the perforated top wall of the carrier is made separate and in the form of a bar 45 having a cam surface 46 adjacent each of its opposite ends which cooperate with similar cam or wedge surfaces 47, 47 formed on the upper surface of the carrier.

Adjacent each cam surface 46 each bar 45 is provided with a longitudinal slot 48 through which the upper non-threaded portions 33 of the screws 31 project. Under the head 34 of the screw 31, in each instance, is provided a slide block 49 which rides on the upper surface of the cam bar 45 and is provided with a key lug 50

which fits into the slot 48 and thereby prevents relative rotation between the slide block and the cam bar, around the axis of the screw. The cam bar in each instance is provided with a knob 51 by which the cam bar may be moved longitudinally.

Longitudinal movement of the cam bar relative to the carrier causes the cam or wedge surfaces 46, 46 on said bar to ride up on the cam surfaces 47, 47 of the carrier whereby the bar 45 is bodily raised vertically while being maintained substantially parallel to the base of the nozzle.

Such vertical movement of the bar 45, through the slide blocks 49 and the heads 34 of the screws 31, effects an axial movement of said screws simultaneously and due to the threaded engagement of these screws with the back bar 30 of the brush the brush is raised bodily to an extent sufficient to withdraw the lower free ends of the bristles of the brush to a position inwardly of the nozzle with respect to the plane of the sledding surface thereof. Such utilization of the screws 31 for moving the brushes to an inoperative position, while remaining in the nozzle, in no way affects the function of the screws to adjust the brush relative to the carrier and to the sledding surface of the nozzle for obtaining any desired degree of projection of the ends of the bristles of the brush relative to the sledding surface of the nozzle as and when the ends of the bristles wear down.

In that form of the invention shown in Figs. 6 and 7, the cam bars 45 are individual to the carriers and brushes with which they are respectively associated and the carriers as a whole and including the individual cam bars are interchangeable in the front and rear slots 17 whereby it is unnecessary for a housewife to be particularly careful in replacing the carriers in the slots after having once removed the carriers from the slots to take advantage of the full benefit of the down draft through the slots in the cleaning of grit, ashes, and other substances from the carpet. In the same manner the carriers 20 in that form of the invention shown in Figs. 1, 2, 3, 4 and 5 are interchangeable.

In that form of the invention shown in Fig. 8, the cam bars 45a, 45a in the front and back slots 17 respectively are adapted for simultaneous operation, rather than independent operation and for this purpose said bars are joined at one end by a cross member 55 in and above which a single operating knob 51a is mounted.

In order to provide for removal of the carriers 20 from the slots 17 in that form of the invention shown in Fig. 8, the slide blocks 50a are provided with lateral slots 56 communicating with the openings 57 through which the screws 31 normally extend. The slots 48a, 48a in the cam bars 45a, 45a respectively are of such width as to permit passage of the heads 34 of the screws 31 therethrough. In order to remove the carriers 20 from the slots 17, raising of the screws 31 a sufficient distance to bring the lower surface of the slide blocks 50a above the upper surface of the cam bars 45a, will suffice to permit said slide blocks to be slipped laterally from beneath the heads 34 of the screws 31, thereby permitting the screw heads 34 to pass through the slots 48a in the cam bars.

In this structure the carriers 20 are preferably held in the nozzle by means of the screws 44 illustrated in Fig. 10, whereby, after the removal of the slide blocks 50a from under the heads of 75

the screws 31, removal of the screws 44 from the opposite ends of the carriers 20 will permit said carriers to be dropped downwardly through and out of the slots 17 in the nozzle.

5 In that form of the invention shown in Figs. 12 and 13 the bristles of the brushes at the opposite sides of the vacuum slot respectively are arranged preferably in a single row side-by-side and substantially parallel to said slot and closely adjacent to the wall 21 of the carrier, in each instance.

Intermediate the brush and the wall 18 in the slot 17, at each side of the vacuum slot 12, and spaced inwardly from the sledding surface 3 of the nozzle, a wire or other relatively small abutment element is provided which extends longitudinally of the carrier parallel to the walls 18 and 21 of the nozzle and carrier respectively.

When the nozzle is moved in one direction 20 transverse to the vacuum slot 12 the carrier 20 forms an abutment for the lower ends of the bristles of the brush whereby they are held stiffly in their raking position as above noted.

When the direction of the movement of the nozzle is reversed the inherent flexibility of the bristles of the brush permits said bristles to flex toward the wall 18 of the nozzle and to slide over the surface being cleaned. During this flexing of the bristles said bristles engage the wire or rod 60 which functions as an abutment for said bristles on a line spaced above the free ends of the bristles whereby said bristles effect a pivotal action around the wire or rod 60 on a relatively short radius, which causes the material-carrying ends of the bristles to rise more quickly and more effectively from the surface being cleaned to deliver the gathered material to the mouth of the suction slot 12 at the lower edge of the wall 18 which, as above noted, is spaced above the sledding surface 3 of the nozzle.

40 In order that a new brush may be readily placed in the carrier, when a brush becomes worn to a considerable extent and thereby shortened to an extent where it is no longer of use, the wire or other abutment 60 is made removable with respect to the carrier so that the bristles of the brush units may be placed easily within the cavities 25 between the ribs 22 on the carrier without having to thread such bristles down between the abutment 60 and the wall 21 of the carrier.

45 In Fig. 13, the abutment 60 is shown as being in the form of an inherently resilient wire, such as a piece of spring or piano wire. The lugs 22 at the opposite ends of the carrier are provided with horizontal openings into which the ends of the wire may be readily placed as by bowing the wire longitudinally, whereafter by releasing the wire, after the opposite ends thereof are aligned with holes 61, 61 in the carrier said wire will automatically assume a rectilinear position, and in order to prevent lateral flexing of the abutment wire 60 relative to the walls 18 and 21 the upper edges of the ribs 22 are notched, as illustrated at 62, to receive the wire when said wire assumes said rectilinear state.

50 In that form of the device shown in Figs. 15, 16 and 17, the vacuum slot 65 is defined by parallel side walls 66 connected by transversely extending end walls 67. The outer surfaces of the side walls 66 are inclined in opposite directions, as indicated at 68, and the bottom edges of the side walls are disposed slightly above the extreme bottom surface of the nozzle.

55 In this instance, the nozzle is provided with

ribs extending laterally from and formed integral with the side walls 66 of the nozzle, as clearly illustrated at 70 in Fig. 15, and at each end of the nozzle, and aligned with the ribs 70, 70, is a lug 71.

Spaced vertically above the upper edges of the ribs 70 and lugs 71 and formed integral with the side and end walls 66 and 67 of the nozzle opening is a horizontally extending rib or plate 72 which completely surrounds the nozzle.

10 The lugs 71 and plate 72 afford bearings for screws 73, 73 which correspond to the brush-controlling screws 31 above referred to.

15 Threaded on to each screw 73, intermediate the lug 71 and the plate 72 is a block 74. Projecting laterally from each block 74 is a trunnion 75 on or in which one end of the brush back 76 is pivotally mounted. Intermediate the perforated plate 72 and the upper surface of the block 74 and surrounding each of the adjusting screws 20 73 is a spring 77 which functions in the manner of the screws 31 as above noted for raising and lowering the tips of the bristles of the brush with respect to the lower surface of the nozzle.

25 One or both ends of each of the brush back bars 76 is provided with a lever, lug or other suitable lateral extension 78 and, at the opposite ends respectively of the nozzle, connecting the levers 78, 78 of the two bars 76, 76 at opposite sides of the nozzle, are links 79, 79, by which 30 rocking of the back bars 76, 76 of the brushes is simultaneously effected.

35 Surrounding the plate 72, the lugs 71, and the outwardly extending ribs 70, is a substantially rectangular band or casing 80 which encloses the brushes and provides the down draft slots 81 by which cleaning of the brushes is effected in the same manner as described above.

40 In this instance, instead of depending upon the flexing of the bristles to move the lower ends thereof from the raking position to the delivery position in the manner above noted, the brushes at the opposite sides of the nozzle are rocked bodily about the axes of the back bars 76, 76, which, as indicated in Fig. 15, causes the brush 45 on one side of the nozzle to abut against the outer removable wall 60 of the nozzle, at one side thereof, and the lower ends of the brush at the opposite side of the nozzle to abut against the inclined side 68 of the side wall 66 of the nozzle, 50 wherein the ends of the bristles of the last mentioned brush are raised clear of the surface being cleaned.

55 The removable wall structure 60 may be secured in place by any suitable means, such for example as by screws 82, the heads of which may be located within a groove 83 completely circumventing the nozzle and in which may be provided a bumper ring 84, whereby marring of furniture contacted by the nozzle is prevented.

60 In the illustration of Fig. 15 the vacuum nozzle is provided with a tapering head 85, the upper edges of which converge toward a hollow neck 86 forming part of the vacuum engine 87 which latter may be provided with suitable supporting 65 wheels 88 which are adapted to ride the surface being cleaned and which, if desired, may be made adjustable relative to said engine whereby the position and/or sledding of the nozzle with respect to or on the surface being cleaned may be 70 governed as desired.

75 The plate 72 is perforated as illustrated at 89 to permit free passage of the air into and downwardly through the down draft slots 81 formed by and between the walls 66 and 67.

In that form of the invention shown in Figs. 18, 19 and 20, the nozzle is relatively short and the bristles are carried in and by a readily removable casing which may be applied to and removed from the nozzle as occasion arises.

The vacuum slot 98 of the nozzle in this instance is defined by side walls 91, 91 and end walls 92, 92 of the nozzle. The brush carrier in this instance comprises side walls 93, 93 and end walls 94, 94 which latter bear directly against the end walls 92, 92 of the nozzle and function as guides for positioning the brush carrier on the nozzle. The walls 93, 93 of the brush carrier are spaced laterally from the side walls 91, 91 of the nozzle.

The brush carrier is provided with a perforated top wall 95 at each side of the nozzle which also assists in guiding the brush carrier into operative position on and with respect to the nozzle.

The lower end of the brush carrier is guided into position on the lower end of the nozzle by the inner edges of the brush-separating ribs 96, 96 which engage the oppositely flaring surfaces 97, 97 formed on and adjacent the lower edges of the side walls 91, 91 of the nozzle.

At each end and at each side of the nozzle and aligned with ribs 96, 96 is a lug 97 which affords pivotal bearing for the lower end of an adjusting screw 98, the upper end and head 99 of which has bearing in the perforated top plate 95 of the brush carrier. The screws 98 on each of the opposite sides of the carrier are threaded through the back bar 100 of a brush whose bristles pass through the cavities formed between the ribs 96, 96 and a spring 101 encircles each of the screws 98 between the top of the back bar 100 and the under side of the top plate 95.

The brush carrier is resiliently secured to the nozzle by spring clips 102 which are secured to the brush carrier and have free ends seated in recesses 103 formed in the side walls 91, 91 of the nozzle.

The brushes 104, 104 and the backs 100, 100 thereof are positioned against the outer walls 93, 93 of the brush carrier respectively in down draft slots 105, 105 provided by and between the nozzle walls 91, 91 and brush carrier walls 93, 93.

The operation of this form of the device is substantially the same as described with respect to the operation of the device shown in Fig. 1.

In Figs. 21 and 22, the abutment for the bristles of the brush disposed at an elevation above the ends of the bristles of the brush to provide for short radius flexing of the brush bristles as and for the purposes above described, in this form of the invention takes the form of a screw 106 which may be readily removed to provide for easy replacement of the brushes.

As shown in Figs. 4 and 14, the handle or wand 110 is disposed at an angle to the surface being cleaned and the axis of the handle intersects the plane of said surface well behind the nozzle, thus the nozzle at all times receives a push-pull action on a line substantially parallel to the surface being cleaned by the nozzle and no digging in of the forward or rear edges of the nozzle is possible. This is also assisted by the wide lips fore and aft on the nozzle which serve an additional function of providing more or less of a seal around the suction slot of the nozzle which necessitates the air entering said suction slot to be drawn down through the draft slot or slots 11.

The down-draft in addition to keeping the brush clean causes the air to pass rapidly around the lower edge of the wall between the down-draft

slot and the vacuum slot in each instance and in so doing the air gets under the dirt or threads on the pile and effectively lifts the same into the suction slot of the nozzle.

The wand or handle 110 is provided with a horizontal extension 111 comprising a portion 112 arranged to be frictionally held or positively locked in the hollow boss of the nozzle and a portion 113 formed by bending the lower end of the wand. The portions 112 and 113 are axially aligned and adapted for relative rotation with respect to each other by means of a swivel joint 114 of any desired construction, which will cause the nozzle to ride uniformly, over the surface being cleaned, from end to end of the nozzle and further permit the handle to be swung down to pass under low furniture, etc., still without tilting the nozzle in either direction whereby the sledding surface of the nozzle will at all times remain substantially parallel and slide freely over the surface being cleaned.

I claim:

1. A cleaner nozzle having a sledding surface provided with a suction slot and a down draft air slot arranged in parallel closely adjacent relation to each other at the lower ends thereof and with the upper end of the draft slot open to the atmosphere, a brush located in said draft slot, and transverse partitions in the draft slot with the lower edges thereof substantially flush with said sledding surface.

2. A cleaner nozzle having a sledding surface provided with a suction slot and a down draft air slot and wherein the upper end of the draft slot is open to the atmosphere, a longitudinal partition between said slots with the lower edge thereof disposed above said sledding surface, transverse partitions in the draft slot with the lower edges thereof substantially flush with said sledding surface, and a brush comprising a plurality of bristle units respectively arranged between said transverse partitions.

3. A cleaner nozzle provided with a suction slot and a down draft air slot arranged in parallel closely adjacent relation to each other at the lower ends thereof and with the upper end of the draft slot open to the atmosphere, a brush carrier removably mounted in the draft slot and comprising a longitudinal side wall, laterally spaced ribs extending transversely of the draft slot from said side wall, a brush mounted in the carrier and comprising a back bar disposed above the transverse ribs and bristles projecting downwardly from said bar between said ribs, lugs at the opposite ends of the carrier above and below said back bar, and adjusting screws mounted in said lugs and having threaded engagement with the opposite ends of said back bar respectively.

4. A cleaner nozzle provided with a suction slot and a down draft air slot arranged in parallel closely adjacent relation to each other at the lower ends thereof and with the upper end of the draft slot open to the atmosphere, a brush carrier removably mounted in the draft slot and comprising a longitudinal side wall, laterally spaced ribs extending transversely of the draft slot from said side wall, a brush mounted in the carrier and comprising a back bar disposed above the transverse ribs and bristles projecting downwardly from said bar between said ribs, lugs at the opposite ends of the carrier above and below said back bar, adjusting screws mounted in said lugs and having threaded engagement with the opposite ends of said back bar respectively, and resilient means between one side of the back bar

and the lugs adjacent thereto for moving the brush in one direction upon rotation of the adjusting screws in one direction.

5. A cleaner nozzle provided with a suction slot and a down draft air slot arranged in parallel closely adjacent relation to each other at the lower ends thereof and with the upper end of said draft slot open to the atmosphere, a brush carrier removably mounted in the draft slot and 10 comprising a longitudinal side wall, laterally spaced ribs extending transversely of the draft slot from said side wall, a brush mounted in the carrier and comprising a back bar disposed above the transverse ribs and bristles projecting downwardly from said bar between said ribs, lugs at the opposite ends of the carrier above and below said back bar, adjusting screws mounted in said lugs and having threaded engagement with the opposite ends of said back bar respectively, resilient 15 means between the top face of the back bar and the under side of the upper lugs tending to move the brush downwardly at all times, and a cam bar slideable longitudinally of the carrier and having operative engagement with the adjusting 20 screws for moving the brush bodily in the upward direction.

6. A cleaner nozzle provided with a suction slot and a down draft air slot arranged in parallel closely adjacent relation to each other at the lower ends thereof and with the upper end of the draft slot open to the atmosphere, a brush carrier removably mounted in the draft slot and comprising a longitudinal side wall, laterally spaced ribs extending transversely of the draft slot from said side wall, a brush mounted in the carrier and comprising a back bar disposed above 30

the transverse ribs and bristles projecting downwardly from said bar between said ribs, lugs at the opposite ends of the carrier above and below said back bar, adjusting screws mounted in said lugs and having threaded engagement with the opposite ends of said back bar respectively, and a longitudinal top wall extending between said end lugs and perforated for sieving the air drawn into the draft slot. 5

7. A cleaner nozzle provided with a suction slot 10 and a down draft air slot arranged in parallel closely adjacent relation to each other at the lower ends thereof and with the upper end of said draft slot open to the atmosphere, a brush carrier removably mounted in the draft slot and comprising a longitudinal side wall, laterally spaced ribs extending transversely of the draft slot from said side wall, a brush mounted in the carrier and comprising a back bar disposed above the transverse ribs and bristles projecting downwardly from said bar between said ribs, lugs at the opposite ends of the carrier above and below said back bar, adjusting screws mounted in said lugs and having threaded engagement with the opposite ends of said back bar respectively, resilient 15 means between the top face of the back bar and the under side of the upper lugs tending to move the brush downwardly at all times, and a cam bar slideable longitudinally of the carrier and having operative engagement with the adjusting 20 screws for moving the brush bodily in the upward direction, said cam bar constituting a closure wall for the upper end of the draft slot and being perforated for sieving the air drawn into the draft slot. 25

JÖRGEN F. H. FECHTBURG.
